NURSERY TIMER OR SIMILAR ARTICLE

Irving Shelton and Edwin L. Whitlock,
New York, N. Y.

Application May 21, 1948, Serial No. 146,506

Term of patent 3½ years

(Cl. D34—4)

To all whom it may concern:

Be it known that we, Irving Shelton and Edwin L. Whitlock, both citizens of the United States, residing at New York, in the county of New York and State of New York, have invented a new, original, and ornamental Design for a Nursery Timer or Similar Article, of which the following is a specification, reference being had to the accompanying drawing, forming part thereof.

In the drawing

Fig. 1 is a top plan view of a nursery timer or similar article, showing my new design;

Fig. 2 is a front view,

Fig. 3 is a rear view,

Fig. 4 is a side view thereof.

The dominant features of our new design are shown in solid lines in the drawing.

We claim:

The ornamental design for a nursery timer or similar article, substantially as shown and described.

IRVING SHELTON.
EDWIN L. WHITLOCK.
